PARTITION ASSEMBLY FOR SHIPPING
CASES

Walter Weidman, Grosse Pointe Village, Mich.

Application November 21, 1933, Serial No. 698,984

5 Claims. (Cl. 206—62)

My invention relates to a new and useful improvement in a partition for shipping cases, adapted for use in cases in which a number of loose parts are to be packed for shipping, and which parts it is desired to maintain in separated relation so as to prevent contact of the parts with each other whereby to eliminate the possibility of marring or damaging the surfaces of the same.

10 The invention is particularly adapted for use in connection with shipping cases in which panels, window frames, windshields and similar articles are shipped.

It is an object of the present invention to provide a shipping case partition structure which may be easily and quickly positioned in the shipping case and removed therefrom, and which will occupy a minimum of space, while affording secure and safe means for maintaining the 20 shipped articles in spaced relation to each other and free from unwanted contact which might injure their surfaces, as well as cushioning the shipped article against shocks.

It is another object of the invention to provide 25 a shipping case partition in which a plurality of separating members may project outwardly from one face of a supporting body.

Another object of the invention is the provision 30 of a partition of this class which will be simple in structure, economical of manufacture, durable, easily and quickly assembled, easily and quickly placed in position in the packing case and removed therefrom, and of slight weight.

Other objects will appear hereinafter.

35 The invention consists in the combination and arrangement of parts hereinafter described and claimed.

The invention will be best understood by a reference to the accompanying drawing which 40 forms a part of this specification, and in which,

Fig. 1 is a perspective view of a packing case showing the invention applied.

Fig. 2 is a sectional view taken on line 2—2 of Fig. 1.

45 Fig. 3 is a perspective view of a modified form of partition.

Fig. 4 is a perspective view of a further modified form of partition.

Fig. 5 is a perspective view of a further modified form of partition.

50 Fig. 6 is a perspective view showing a further modified form of partition in use.

Fig. 7 is a fragmentary plan view of a portion of the supporting plate used in Fig. 6.

55 In Fig. 1 I have illustrated the invention used

with a packing case having opposite side walls 12 and 13, and end wall 14 and 15. The partition embodies a supporting body or plate 16 which may be formed from cardboard, fibre paper, wood or any other suitable material. Secured to the supporting plate 16 at spaced intervals are the dividing plates 17 which have the ends 18 and 19 turned outwardly from the face of the supporting plate 16 to form a substantially U shaped structure. These dividing strips 17 may be secured to the supporting plate 16 in any suitable manner. I have illustrated the same, however, secured thereto by staples 20. In use, the partition is positioned as illustrated, two of the partitions being used in each packing case. 10 One of the partitions is positioned with the supporting plate 16 in engagement with the wall 13 and the other is positioned with the supporting plate in engagement with the wall 12. The material to be packed is illustrated in the form of plates or panels 21. It will be noted that on one of the supporting plates 16, the endmost partition member A is located so as to terminate flush with the end of the board 16. At the opposite end, the board or supporting plate 16 terminates free from any dividing members so that a portion of this board projects beyond the endmost of the dividing members. The complementary partition is reversed as to position in this regard, and the dividing member B is positioned at the end of its supporting board so that the outwardly projecting free end of this supporting board lies opposite to the dividing member A. This causes a non-alignment of the dividing members on the opposite partitions 25 which are complementary to each other so that the plate or panel 21 engages at one of its edges between a pair of legs 18 and 19 and at the other edge between a pair of the strips 17. This arrangement is such that while the members 21 are maintained in spaced relation and prevented 30 from contacting with each other, a minimum amount of space is consumed.

In the various forms illustrated in Figs. 3, 4 and 5, the partitions are used in complementary 45 pairs as illustrated in Fig. 1.

The form of partition illustrated in Fig. 3 is exactly the same as illustrated in Fig. 1 and Fig. 2, except that the supporting plate is eliminated and a pair of supporting strips 22 and 23 are substituted therefor. This construction differs from the construction shown in Fig. 1 and Fig. 2 only that the central part of the supporting plate is eliminated so as to save in material and reduce the weight.

In Fig. 4 I have illustrated a partition formed preferably from a single sheet of material in which a back or supporting plate 24 is provided. The strip of material from which it is made is doubled upon itself at one end, and this doubled over portion is doubled upon itself to provide a plurality of spaced channels 25 which are substantially U shaped in cross section. This construction will, of course, space the plates packed in the case farther apart, but the width of the spacing member 25 will also accommodate projections which may be found on the ends of the plates packed therein.

In Fig. 5 the structure is similar to that shown in Fig. 3 excepting that instead of securing the strips 26, which correspond to the strip 17 shown in Fig. 1 or the strip 17' shown in Fig. 2, to the supporting members 22' and 23', I provide slits 27 through which the supporting members 22' and 23' are slidably projected. While this does not form as rigid a structure as that shown in Fig. 1, Fig. 3 or Fig. 4, it provides a structure sufficiently rigid for the purposes intended while at the same time the members 26 may be adjusted to various widths of spacing as indicated in Fig. 5, thus affording a packing case partition adapted for use on articles of various kinds.

In Fig. 6 I have illustrated a form of partition which is adapted for use with packing cases in which U shaped or L shaped articles are packed. In Fig. 6 I have illustrated the invention used in packing the U shaped article having the bight 23 and the legs 29 and 30. In the same casing I have illustrated the U shaped member comprising the bight 31 and the legs 32 and 33. The separating members comprise the U shaped bodies 34. Interlocking with these separating members is the supporting body 35 having the slits 36 formed inwardly from one end cooperating with similar slits formed inwardly from the opposite end of the strips 34. On one end of the supporting body 35 is a flap 38 and on the partition C this flap 38 is positioned at the top while on the partition D this flap is positioned on the bottom. The construction is such that the U shaped member embodying the bight 31 has its leg 32 engaging in the channel 39 and its opposite leg engaging between the free ends of the legs of the oppositely positioned dividing strip 34. The bight 31 rests upon the flap 38. When these U shaped members are packed in this manner so that all of the spaces are filled, the casing 40 which I have indicated in dotted lines, is inverted and the device packed from the opposite side, in which case the bight 23 overlies the flap 38 on the partition D and the leg 29 engages in the channel 39 of the partition D, while the leg 30 engages between the free ends of the separating members 34 of the partition C. Thus I pack a plurality of U shaped bodies in overlapping relation, spaced from each other, and free from contact with each other. It is obvious that this arrangement permits of a maximum number of articles to be so packed in a minimum amount of space.

With a packing partition constructed and arranged as described, an easy and safe transporting of articles of this class may be effected with a minimum amount of space and weight. It is

also believed obvious that the partitions themselves may be quite economically manufactured.

While I have illustrated and described the preferred forms of structure of my invention, I do not wish to limit myself to the precise details of structure shown, but desire to avail myself of such variations and modifications as may come within the scope of the appended claims.

Having thus described my invention, what I claim as new and desire to secure by Letters Pat- 10 ent is:

1. In combination, a packing case having oppositely disposed walls; a pair of partition members positioned in said case adjacent the inner surface of each of said walls, each of said partitions comprising a supporting body and a plurality of channel-shaped spacing members projecting inwardly from the inner face of said supporting member in spaced relation, the supporting member of one of said partitions projecting 15 beyond the endmost of said dividing members, and the opposite side of the opposite partition projecting beyond its endmost dividing member.

2. A packing case partition of the class described, comprising a plurality of channel forming spacing members substantially U shaped in cross section; and a plurality of supporting strips 25 for supporting said members, said members being slidable on said supporting strips.

3. In combination, a packing case having oppositely disposed walls; a pair of partition members each positioned adjacent the inner surface of one of said walls and each of said partitions comprising a supporting body, a plurality of channel forming spaced separating members projecting 35 inwardly of the casing and a foldable flap on the end of said supporting body for engagement with the end edges of said separating members, the flap on one of said bodies being positioned at the top and on the other of said bodies on the 40 bottom, said separating members providing channels in each of said partitions at opposite sides of its supporting bodies.

4. A packing case partition comprising: a plurality of elongated channel-shaped separating 45 members having spaced slots formed in the legs thereof adjacent the bight and an elongated supporting strip projecting through corresponding slots of a plurality of said members for mounting the safe in spaced relation.

5. In combination a packing case having oppositely disposed side walls and oppositely disposed end walls; a pair of partition members positioned in said case adjacent the inner surface of each of said side walls, each of said partitions comprising a supporting body and a plurality of channel-shaped spacing members projecting inwardly from the inner face of said supporting members in spaced relation, the legs of the channel-shaped members on one of the said supporting members being faced toward the legs of the other, the innermost spacing member at one end of said supporting member being positioned with the outer face of its outer leg flush with the end of the supporting member and the supporting 60 member at the opposite end projecting beyond the endmost spacing member, said supporting members being positioned in said packing case in reversed position relatively to their ends.

WALTER WEIDMAN.
